US0D1039678S

(12) **United States Design Patent** (10) **Patent No.:** **US D1,039,678 S**
(45) **Date of Patent:** **** Aug. 20, 2024**

(54) **SUCTION APPARATUS**

(71) Applicant: **Bug Bite Thing Europe ApS**,
Hørsholm (DK)

(72) Inventor: **Ivan Runge Andrés**, Rungsted Kyst
(DK)

(73) Assignee: **Bug Bite Thing Europe APS**,
Horsholm (DK)

(**) Term: **15 Years**

(21) Appl. No.: **29/788,030**

(22) Filed: **Feb. 18, 2021**

(30) **Foreign Application Priority Data**

Oct. 30, 2020 (EM) 008220065-0001

(57) **CLAIM**

The ornamental design for a suction apparatus, as shown and described.

DESCRIPTION

FIG. 1 is a top, left, front perspective view of a suction apparatus showing my new design, with a cap in a first orientation and a handle in a retracted position;

FIG. 2 is a rear elevational view of the suction apparatus shown in FIG. 1;

FIG. 3 is a top, left, front perspective view of a suction apparatus showing my new design, with the cap in a second orientation and the handle in the retracted position;

FIG. 4 is a right side elevational view of the suction apparatus shown in FIG. 1, with the cap in the second orientation and the handle in an advanced position;

FIG. 5 is a left perspective view of the suction apparatus shown in FIG. 1, with the cap in the second orientation and the handle in the retracted position;

FIG. 6 is a bottom perspective view of the suction apparatus shown in FIG. 1, with the cap in the second orientation; and, FIG. 7 is another front perspective view of the suction apparatus shown in FIG. 1, with the cap in the second orientation and the handle in the retracted position.

1 Claim, 7 Drawing Sheets
